UNITED STATES, PATENT OFFICE.

CHARLES H. TOMLINSON, OF MANSFIELD, OHIO, ASSIGNOR TO THE TOMLINSON COUPLER COMPANY, OF MANSFIELD, OHIO, A CORPORATION OF OHIO.

COUPLER-SUPPORTING MECHANISM.

Original application filed January 17, 1924, Serial No. 686,903. Divided and this application filed February 14, 1925. Serial No. 9,151.

To all whom it may concern:

Be it known that I, CHARLES H. TOMLINSON, a citizen of the United States of America, residing at Mansfield, in the county 5 of Richland and State of Ohio, have invented certain new and useful Improvements in a Coupler-Supporting Mechanism, of which the following is a specification.

My invention relates to a supporting device for car couplers and has for its objects 10 a device which will yield vertically when undue pressure is brought upon the supporting device in a downward direction, and another object of my invention is to permit 15 the coupler to move laterally of the car as is required when cars equipped with pivotally mounted couplers swing around a curve of short radius. Another object of my invention is to provide a support for 20 couplers which will have a centering action to maintain the couplers in a normally central position when the cars are uncoupled thereby placing them in a position where they will couple automatically upon impact 25 without the necessity of an operator moving the couplers to a central position. A still further object of my invention is to provide a supporting device which will permit a relative rotation of the supporting device 30 with respect to the coupler, as this is advisable in case of a train of cars hauling materials and which it is desired to dump the material by rotating the whole car.

This application is a division of my co- 35 pending application, Serial No. 686,903, filed January 17, 1924.

My invention resides in the new and novel construction, combination and relation of the various parts herein described 40 and disclosed in the drawing accompanying this specification.

In the drawings:

Fig. 1 is a front or face view in partial section of my supporting and centering mechanism and a sectional view of the coupler draw-bar or tail-piece in normal relation thereto.

Fig. 2 is a front or face view in elevation of the mechanism shown in Fig. 1 and 50 also of the coupler draw-bar to show their relation when the car to which the mechanism is secured is in a rolled-over position.

Fig. 3 is a top view of the mechanism

shown in Figs. 1 and 2 without the coupler tail-piece.

Fig. 4 is an end view of Fig. 1.

Fig. 5 is a sectional view on the line 5—5 of Fig. 3.

In the preferred embodiment of my invention I employ a supporting yoke 1 to 60 the ends of which are secured the spring hangers 2. The spring hangers comprise a barrel-shaped member 3 and an inwardly projecting flange 4 at the lower end and having an opening therein through which 65 passes the supporting bolt 5 which is provided with an enlarged head 6 at its upper end. Between the head 6 and the flange 4 is interposed a spring 7 which tends to move the bolt 5 upwardly. The lower end 70 of the bolt 5 is provided with a cross-wise or T shaped member 8 provided with a transverse hole to receive a pin 9 by means of which the supporting yoke and the spring hanger are secured together.

The yoke member 1 comprises end casings 10 having a recess 11 through which passes the bolt 5. At the inner side of the member 10 is a projecting stud 11' which receives the pipe or tubing 12. The member 12 is secured to the member 11 by means of the through bolt 13 and secured to the center of the member 12 is a collar 14 secured in place by means of the through bolt 15. Connecting the members 10, in addition to the pipe 12, are the spaced members 16 forming the outer faces of the yoke. The members 10 and 16 are held together by means of the through bolts 17 and the bolts 13 and 15. The side members 16 85 are provided with the outwardly projecting flange 18 upon which rest the laterally movable members 19.

The members 19 provided with a downwardly projecting member 20 provided with 90 an opening through which passes the tubular member 12 and is also provided with a flanged portion 21 resting upon the flange 18 and upon which the members 19 slide laterally. The laterally movable or holding members 19 are provided with the upright members 22 between which is positioned the coupler draw-bar or tail-piece 23. The holding members 19 are normally held central 100 of the mechanism by means of the spring 105 24 interposed between the holding member

20 and the end member 10, which moves the holding members into engagement with the central collar 14 or a position adjacent thereto. The holding members are so designed as to unite along a central line 5-5, or substantially so, but in order to prevent an opening between the members 19 when moved relatively away from each other, one or both of the members are provided with a 10 projection 25 which will provide a seat for the coupler tail-piece 23 when the members 19 separate.

In order to permit the tail-piece 23 to rotate relative to the supporting mechanism 15 and also to provide cooperating means tending to hold the coupling mechanism and the supporting mechanism in a predetermined relation under normal operating conditions, I find it advisable to provide the tail-piece 20 with a plurality of flat faces and to have a sufficient number of flat faces so that their width will not be so great as to prevent the roll-over action between the coupler and the supporting device. In the roll-over action 25 it will be noted that it is necessary for the members 19 to move apart and this is brought about by the relative rotation of the member 23 with respect to the supporting device. If the tail-piece 23 is provided 30 with only four sides I find that this is very liable to resist relative rotation more than is necessary and advisable, but I find that if it is provided with six or eight faces it is very satisfactory, in that, they present a sufficient 35 width to cooperate with the members 19 to hold the coupler in normal position under regular operation, but not to resist the rotation of the parts to too great a degree in the roll-over operation.

40 The inner engagement between the member 20 and the tubular member 12 prevents the displacement of the member 19, but does not prevent its lateral movement.

The members 3 may be provided with the 45 supporting bar 26 for securing the device to the under-framing of the car or other means may be substituted for the member 26.

It will be apparent that when cars are 50 equipped with my supporting mechanism and the couplers are secured to the car by means of a ball and socket connection which will permit rotation of the coupler about its longitudinal axis and also vertical and lateral swinging movement about the connection 55 to the car, that my supporting device will permit the vertical and lateral movement of the coupler and will also permit a roll-over operation of the car relative to the coupler. My device will also tend to 60 maintain the coupler in a normal position with respect to the car under normal operation, and it will also tend to move the coupler 2 and maintain it in a central position when not coupled to an adjacent car. My 65 invention also tends to normally support the

coupler at a fixed height above the track providing the car body maintains a fixed relation with respect to the track, but permits the coupler to yield vertically as is required when cars pass over a break in the grade. 70

Modifications will be apparent to those skilled in the art, but I do not wish to be limited other than by my claims.

I claim:

1. A centering and supporting device comprising in combination, a transverse yoke member, spaced support members having means to rigidly secure them to a car body to prevent lateral movement of the yoke member, a member pivotally secured to each end of the yoke member and projecting in telescopic relation to one of the support members, a spring interposed between each pivotal member and its support member to permit the said members to yield vertically 80 under stress and tending at all times to return the members to their normal position, a transverse member secured to the yoke member and having a pair of spaced springs mounted thereon, a collar mounted on and secured to the transverse member intermediate its ends, and a pair of laterally and independently movable members mounted on the yoke member to support a coupler and each having depending means interposed between one of the springs and the collar and movable in a direction away from the collar when the coupler stresses either of the movable members away from the collar. 90

2. A centering and supporting device comprising in combination, a yoke member, spaced supports having means to rigidly secure them to a car body, a member pivotally secured to each end of the yoke member and projecting in telescopic relation to one of the supports, a spring interposed between each pivotal member and its support to permit the said parts to yield vertically under stress, but tending to maintain the parts in a predetermined relation, spring supporting means secured to the yoke member, a pair of independent coupler supports slidably mounted upon the yoke and having holding means to engage the spring supporting means to prevent the upward displacement, a pair of spaced springs mounted on the spring supporting means and engaging the holding means to move the coupler supports to the center of the yoke. 100

3. A centering and supporting device comprising in combination, a yoke member, yielding means securing each end of the yoke member to a car body to prevent lateral movement of the yoke member relative to the car body and pivotally connected to the yoke member to allow each end of the yoke member to yield vertically independently, a spring support mounted on the yoke member and a pair of springs mounted on the spring support, a pair of slidably mounted 110

ed members interlocked with the spring support and each member engaging one of the springs and held central of the yoke member by the spring to maintain a coupler normally central of the yoke and means to prevent the springs from moving the slidably mounted members beyond the center of the yoke.

4. The combination with a coupler support to be attached to a car body of a pair of coupler seats adapted to move toward and away from each other and yielding means to normally hold the seats in adjacent relation, each seat having a horizontal and a vertical face connected by an obliquely disposed face to correspond to and to receive therebetween a coupler shank having corresponding faces.

5. The combination with a coupler support to be attached to a car body of a pair of seat members adapted to move toward and away from each other and receive a

coupler shank therebetween and yielding means to normally hold the seats in adjacent relation, each seat having a vertical face and a downwardly and inwardly inclined face corresponding with similar faces on the coupler shank.

6. A coupler supporting device comprising a yoke member, a spring supporting member mounted on the yoke member, a pair of seat members movable relatively away from each other and mounted on the yoke member to support a coupler stem, horizontal overlapping portions on each seat to form a supporting surface for the coupler stem on each seat at all times and resilient means on the spring support to yieldingly maintain the seats in adjacent relation but permitting separation under stress.

In testimony whereof I affix my signature,
CHARLES H. TOMLINSON.
